UNITED STATES PATENT OFFICE.

WINFIELD A. GRAYBEAL, OF LANSING, NORTH CAROLINA.

FIRE-SCREEN.

1,307,817.

Specification of Letters Patent. Patented June 24, 1919.

Application filed March 24, 1919. Serial No. 284,565.

To all whom it may concern:

Be it known that I, WINFIELD A. GRAYBEAL, a citizen of the United States, residing at Lansing, in the county of Ashe and State of North Carolina, have invented new and useful Improvements in Fire-Screens, of which the following is a specification.

This invention relates to screens adapted to be used in front of fire-places for preventing the escape of sparks from the fire into the room, and also for preventing children and others from coming too close to the fire and getting burned.

The invention has for its object to provide a novel and improved device of this kind which is readily adjustable to fire places of different dimensions, and which is also foldable into small and compact form for convenience in storage when not in use.

The object stated is attained by means of a combination and arrangement of parts to be hereinafter described and claimed, and in order that the same may be better understood, reference is had to the accompanying drawing forming a part of this specification.

In the drawing,

Figure 1 is a plan view of the invention, a fragment of the fire-place being shown in section;

Fig. 2 is a front elevation of the screen, and

Fig. 3 is a sectional detail on the line 3—3 of Fig. 2.

Referring specifically to the drawing, 5 denotes the opposite side walls of a fire-place. The screen associated with the fire-place comprises a main front section 6, and side sections 7, each of these sections being 10 made up of ordinary wire screen material. Back of each screen section is placed a sheet 8 of fine mesh screen cloth of proper dimensions to completely cover the sections. These sheets have hooks 9 at the top for separable 15 attachment to the sections, and they are provided for the purpose of entirely preventing passage of sparks through the screen.

The frame of the main screen section 6 is composed of tubular end bars 10 connected by longitudinal top and bottom bars 11 and 12, respectively. The screen fabric is secured in this frame in any suitable manner, and the sheet 8 back of the same is supported by slipping the hook 9 over the 20 top bar 11.

The frame of each side section is com-

posed of end bars 13, and top and bottom bars 14 and 15, respectively. The hooks of the backing sheets 8 of these sections are also engaged over the top bars for supporting said sheets. The end bars 13, adjacent to the end bars 10 of the main screen frame, are pivotally connected or hinged to the top and bottom bars 11 and 12, the latter bars having apertured extensions to receive the ends of the bars 13. The extensions of the top bars 11 are clearly shown at 16 in Fig. 1. It will therefore be seen that the side screen sections are hinged to the main section, which permits them to be folded 70 inward against the back of the latter as shown in dotted lines in Fig. 1.

The following means are provided for supporting the screen sections 6 and 7 in upright position in front of the fire-place:

Across the fire-place extends a horizontal rod composed of two telescoping sections 17 and 18, respectively, the former being tubular to seat the latter. The rod can therefore be lengthened or shortened according to the width of the fire-place, and the sections are locked in adjusted position by a set screw 19 threaded through the section 17 to engage the section 18. On the outer end of the sections 17 and 18 are shoes 20 85 engaging the side walls 5 and carrying set screws 21 adapted to be screwed in to bear against said walls as clearly shown in Fig. 1.

Extending outwardly from the rod sections 17 and 18 are two horizontal supporting arms for the screen section 6. Each of these arms is composed of two telescoping sections, the inner section 22 being tubular to receive the outer section 23, and a set screw 24 being provided to lock the sections 95 in adjusted position.

To the rod sections 17 and 18, near their outer ends are secured cuffs or similar members 25 having forwardly and horizontally projecting portions 26 which are apertured to loosely seat the hook-shaped inner ends 27 of the arm sections 22, said ends being downturned. This structure provides a detachable connection between the rod sections 17 and 18 and the arm sections 22 carrying the sections 23, in view of which the sections 22 and 23, after the latter are disconnected from the rod sections may be swung to come along the top of the screen 6.

The supporting arm sections 23 have 110 downward bends 28 at their outer ends which seat slidably and rotatably in the end

bars 10 of the screen 6, said bars being tubular, as shown in Fig. 3. The arm sections can therefore be swung around to the top of the screen 6 as described, and the entire 5 supporting structure can be raised or lowered to suit the particular fire-place structure, by sliding the bends 28 up or down in the bars 10. A set screw 29 is threaded through the end bars 10 to engage the bends 10 28 and lock the same in said bars and thus hold the arm sections 22 and 23 firmly when folded on top of the screen 6, and also when in holding position.

It will be evident from the foregoing that 15 the supporting means have a wide range of adjustment and permit ready attachment to any fire-place of ordinary construction, and when not in use, the parts can be folded into smaller compact form for convenience in 20 storage. As the arm sections 23 can be extended more or less from the sections 22, the screen can be spaced any desired distance from the fire-place; the side sections 7 being folded back to the jambs of the fire-place as 25 shown in Fig. 1, so that the fire-place is now completely closed in.

I claim:

1. The combination of a horizontal supporting member having means for attachment to a fire-place, a fire-screen, and supporting arms for the screen pivotally connected thereto, and detachably connected to the supporting member to fold along the screen when detached from the supporting 30 member.

2. The combination of a horizontal supporting member having means for attachment to a fire-place, and composed of a pair of extensible rods, a fire screen, and supporting arms for the screen pivotally con- 35 nected thereto, and detachably connected to the supporting member to fold along the screen when detached from the supporting member.

nected thereto, and detachably connected to the supporting member to fold along the screen when detached from the supporting member.

3. The combination of a horizontal sup- 45 porting member having means for attachment to a fire-place, a fire screen, and supporting arms for the screen pivotally connected thereto, and detachably connected to the supporting member to fold alongside 50 the screen when detached from the supporting member, said arms being composed of extensible sections.

4. The combination of a horizontal sup- 55 porting member having means for attachment to a fire-place, a fire screen, and supporting arms for the screen having downturned outer ends, and detachably connected at their inner ends to the supporting member, the screen having tubular end bars in 60 which said downturned ends loosely seat.

5. The combination of a horizontal sup- 65 porting member having means for attachment to a fire-place, a fire screen, and supporting arms for the screen having downturned outer ends, and connected at their inner ends to the supporting member, the screen having tubular end bars in which said downturned ends seat.

6. The combination of a horizontal sup- 70 porting member having means for attachment to a fire-place, a fire screen, supporting arms for the screen having downturned outer ends, and connected at their inner ends to the supporting member, the screen having 75 tubular end bars in which said downturned ends seat, and means for locking said downturned ends in the end bars.

In testimony whereof I affix my signature.
WINFIELD A. GRAYBEAL.
